UNITED STATES PATENT OFFICE.

NORRIS D. STEWART, OF SAN ANTONIO, TEXAS.

MACHINE FOR TRANSLATING ROTARY INTO RECIPROCATING MOVEMENTS.

1,384,360.

Specification of Letters Patent. Patented July 12, 1921.

Application filed July 19, 1917, Serial No. 181,583. Renewed October 15, 1920. Serial No. 417,265.

To all whom it may concern:

Be it known that I, NORRIS D. STEWART, a citizen of the United States, residing at San Antonio, in the county of Bexar and State of Texas, have invented certain new and useful Improvements in Machines for Translating Rotary into Reciprocating Movements, of which the following is a specification, reference being had therein to the accompanying drawing.

This invention relates to improvements in mechanism of the class including those each of which comprises a rotary driving element and a reciprocating power imparting element; the object being to provide a mechanism which can be operated with the utmost economy, relative to consumption of power, time, and amount of work done.

The improvements which I have made are particularly advantageous in machines used in compressing materials in forming bales, as, hay, for example. And for clearly setting forth an embodiment of the features of construction and operation which characterize my invention, I have illustrated and will describe a hay press as typical of the machines which can be constructed in my improved manner. When one of these machines is in operation its successively working movements may be regarded as occurring in cycles, a forward or working stroke and a return or idle stroke constituting one of these cycles. When the power transmitting parts of the plunger are returned from the limit of its forward movement to the limit of its rearward movement, they may be regarded as unloaded, and during this movement or stroke there is practically no work at all being done, and at such time it is desirable that the plunger should be returned with as high a speed as is possible within the limit of safety for the parts.

When the plunger, however, is moving in the opposite direction, it passes through three stages whose differences are well defined so far as the amounts of work done in them, respectively, are concerned. As it is moving from its initial position through the receiving chamber it moves comparatively easily for the first two-thirds, (or thereabouts) of its total travel. Then it begins to experience severe resistance for two-thirds of the remainder of its path, and during the last few inches of its travel it is powerfully resisted.

The mechanism which I have designed is

intended to move the plunger of one of these machines in such a way that high speed can be attained on the return stroke with a minimum consumption of power, and that on the forward stroke it increases in power and decreases in speed in a manner conforming to the facts above specified.

In the drawings, Figure 1 is a side elevation of a hay press having parts constructed and related in such a way as to embody my invention.

Fig. 2 is a top plan view.

Fig. 3 is a rear elevation of the parts shown in Fig. 1.

Fig. 4 is a diagrammatic illustration showing the parts and positions which they occupy at the time of the commencement of a return stroke.

Fig. 5 is a similar view, illustrating the parts and their positions during the return stroke.

Fig. 6 is a similar view, showing the parts at the time when the plunger has reached the end of its return stroke.

Fig. 7 shows the parts in the positions occupied at the time when the plunger has made about two-thirds of its forward stroke.

A suitable frame is provided for firmly holding the moving parts of the mechanism, that shown having longitudinal bottom sills 1, 1, top sills 2, 2, bottom cross bars or girts 3, 3, top cross bars 4, 4, and binders 4^a, 4^a, of a suitable character and number.

This frame may be extended beyond the limit indicated for the purpose of supporting an engine or motor directly upon the structure itself. The engine, however, can be separately supported on its own carriage.

Of those parts stationary in relation to the frame which directly assist the relatively movable parts in receiving and transmitting power, the important ones are the uprights 5, 5, one at each side of the frame and rigidly secured to the sills and the cross bars. This power frame, if necessary, may be strengthened by braces 6, 6, and other similar devices.

Transporting wheels of any suitable character, such as those at 7, 7, may be provided with their axles mounted in bracket bearings B.

The frame supports the hopper or receiving guide at 10, which in detail may be of any preferred form. As illustrated, it has inclined walls 11 which guide the material to the mouth 12 or entrance of the receiving

chamber 13, where it is first received from the hopper and held until it is impinged upon by the plunger 14.

The compressing chamber is indicated 5 at 14^a.

Upon the top of the uprights 5 the drive shaft 15 is mounted in bearings 16, secured to this part of the frame. This shaft is provided with a power receiving pulley 17, 10 adapted to be connected by a belt to an engine or counter-shaft. It also has two pinions 18, 18, in vertical planes immediately inside of those of the uprights 5. Each of the latter is formed with a guideway 19 having an upper element 20 and a lower element 21 at a predetermined inclination to each other. These guides are provided, in the mechanism shown, by constructing uprights 5 of relatively wide, strong plates in 15 which slots are formed.

22 is a swinging arm or lever pivotally mounted loosely at its upper end on the drive shaft 15. At its lower end it is pivoted to the pitman 23 of the plunger 14. The 25 movements of the plunger are caused by the oscillations of this lever arm 22.

To effect variable movements of the lever arm use is made of the following devices: they include two large gear wheels 24, 24, 30 spaced apart, one on one side of the lever arm 22 and the other on the other. They are supported on the arm by means of a through shaft 25, whose axis is between the axes of the pitman pivot 23^a and of the 35 drive shaft 15.

The wheels can swing backward and forward with the arm and can simultaneously rotate around the axis of the shaft 25. Their rotation is caused by the pinions 18, 40 18, on the drive shaft 15 engaging with them.

The reciprocating or swinging movement of the wheels 24, bodily, is effected by means of projections extending laterally outward 45 from the outer faces of the wheels, respectively, these projections passing through the guideways 19 and engaging with the edge walls. Each projection comprises a pin or stud shaft 27 and an anti-friction 50 roller 28. As shown, (Fig. 3) each of the rollers is grooved and engages transversely or laterally with the walls of the guideways. The axis of the projecting pins or studs 27 is eccentric to the axis of the shaft 25 around which the wheels 24 rotate. When they are rotating under the force 55 from the driving pinions 18 the pins 27 and the rollers 28 are caused to move upward and then downward in the guide slots 20, 60 21. The rotary motion of the wheels 24, in conjunction with the action of the projections in the guides, results in the swinging of the wheels 24 and of the lever arm 22 backward and forward.

65 The hay is pressed or packed downward

by means of the feeder plunger 29. This is pivoted at 30 to a vertically vibratable carrier formed of one or more arms 31. The packer or feeder 29 is held in proper position relatively to the vertical (approximately in vertical parallelism) throughout its movements by the parallel rule rod 33 pivoted at the upper end of the packer and also pivoted to an upright 34 secured to the top part of the power frame. The packer 75 is moved down and up by devices connected to the pitman 23, these including a link 35 and the bell crank lever 36, hinged at 37 to the pivot or shaft of the packer arm 31.

When the plunger 14 moves backward the 80 link 35 draws down on the bell lever 36 and on the packer arm 31, the latter carrying the packer 29 downward into the hopper and into the receiving chamber. As the plunger 14 returns on its forward stroke the link 85 35 causes the upward movement of the arm and the lifting of the packer.

At 38, 39, are indicated the block dropping devices, which may be of any suitable or preferred sort.

The operation of the mechanism above described will be readily understood. Assuming that the plunger is at the forward limit of its movement, as shown in Fig. 1, and that a charge of hay is in or ready to 90 be deposited in the hopper, and that the belt pulley 17 has been set in operation, the prime pinions 18 commence to rotate the large gear wheels 24, 24 in the direction indicated by the arrow. These, as soon as 95 they begin to rotate, cause the projections and the rollers 27, 28, to move upward in the part 20 of the guide 19. These serve as movable fulcrum and the lever arm 22 is caused to swing backward as in Fig. 5. 100 The plunger is drawn also backward; the link 35 pulls the packer downward and the charge of hay is forced from the hopper into the receiving chamber just as the plunger 14 leaves it, this being the charge with 105 which the plunger will engage on its next forward stroke. The wheels 24, under the power, continue to rotate in the same direction. Their axis and the shaft 25 swing 110 backward under the projections 27 and then rise on the rear side relatively to the projections; that is to say, during the movements referred to the lever arm 22 has 115 swung backward from the position shown in Fig. 4 to the position shown in Fig. 6. 120 The fulcrum roller at 27 has first risen relatively somewhat and then begun to move downward. During this period the traveling fulcrum has been so positioned relatively that the swinging of the arm has 125 been with increasing rapidity.

The wheels 24 continuing to revolve on their axis in the same direction, the fulcrum projections and the rollers 27 begin to travel through the element 21 of the guideways. 130

As the lever arm 22 is pushing the plunger forward during the first two-thirds of the power stroke, the fulcrums are in such position that the speed of swing of the arm is still somewhat high, although less than when the arm was moving from its forward limit to its rear limit. The parts during this period have moved from the positions shown in Fig. 6 to those shown in Fig. 7. The movements of the parts continue with a further advance of the plunger, which has now commenced to compress somewhat powerfully the charge of hay, this movement continuing, say, during six inches of the plunger's travel forward. The shifting fulcrums in this period have been in such relative positions that the speed of the swinging arm has been considerably reduced, but the power which it exerts has been relatively increased.

A few, say three, inches of travel forward remain for the plunger. The movable fulcrums are at this time in those parts of the guideways where the speed of travel is reduced to the minimum but the greatest power is exerted, the change in positions of the parts being noted upon comparing the positions shown in Fig. 7 with those shown in Fig. 4.

A block having been (by assumption) put properly in place, the compressed bale is ready for tying in the usual way.

The plunger is now at its forward limit and the gear wheels 24, continuing to revolve, the cycle of movements above described is repeated.

I am aware that hay presses have been made in each of which there was use in the train of parts, between the plunger and the initial power devices, of one or more eccentric wheels—generally a pair of toothed gear wheels mounted on bearings eccentric to their axes, which latter are stationary relatively to the frame. They are driven by toothed pinions which move bodily to compensate for the relative peculiar movements of the wheel, and with the parts are generally combined variable belt driving devices to compensate, in turn, for the movements, bodily, of the pinions, their shaft, and the driven belt pulley.

The eccentric wheels are large and heavy, and the results brought about by moving them around bearings which are eccentric to their axes I have found very disadvantageous. And again, the parts required to effect all of the compensations are numerous, and the machines are complicated and not durable.

In my construction the large transmitting gear wheels are supported at their central axes, and while the driving shaft is moving uniformly the large wheels rotate with a constant predetermined speed. The drive shaft is in fixed bearings, no compensators

of any form are required, and the number and character of the power transmitting parts are reduced to a minimum.

While I have above quite specifically described the form and arrangement of each of the parts found in the illustrated machine, the following will be observed. The centrally mounted wheels 24 have not only a motion of rotation around their central axes but they are also bodily movable with those axes through a predetermined path, and while traveling through the successive parts of that path, their bodily movements are translated into movements of the plunger, which vary in the way and for the purposes above described.

As concerns speed and the imparting of power: The means for varying the speed and the power delivered may be regarded as devices which, with varying forces, resist these bodily movements of the wheel. In the illustrated mechanism there is an abutment, which is stationary relatively to the wheels, and a shifting fulcrum movable synchronously with the wheels, and in proper directions, and bearing first at one point and then at another upon the said abutment, the abutment being, as aforesaid, a device for resisting the movement of the fulcrum with varying amounts of force.

I have described in detail the specific mechanism which I have selected to typically illustrate machines which can embody my improvements; and it will be understood that I do not limit myself in this respect.

What I claim is:

1. The combination with the plunger of power transmitting devices connected to the plunger and comprising a bodily movable wheel rotating around its central axis, a shifting fulcrum moving in synchronism with the bodily movements of the wheel, and means independent of the wheel for resisting the movement of the fulcrum with varying amounts of force.

2. The combination with the plunger of power transmitting devices connected to the plunger and comprising a bodily movable wheel rotating with substantially constant speed around its central axis, a shifting fulcrum moving in synchronism with the bodily movement of the wheel, and means independent of the wheel for resisting the movement of the fulcrum with varying amounts of force.

3. The combination with the plunger of power transmitting devices connected to the plunger and comprising a bodily movable wheel rotating around its central axis, a shifting fulcrum movable in synchronism with the bodily movement of the wheel, a relatively stationary abutment for the fulcrum along which it moves and with which it constantly engages throughout each stroke of the plunger, and means for resisting the

movement of the fulcrum along the abutment with varying amounts of force.

4. The combination with the plunger of power transmitting devices connected to the plunger and comprising a bodily movable wheel rotating with a substantially constant speed around its central axis, a fulcrum which is shifted by the rotary movement of the wheel, and an abutment for the fulcrum along which it shifts and which resists its movements with varying amounts of force.

5. The combination with the plunger of power transmitting devices connected to the plunger and comprising a power driven wheel rotating around its central axis and bodily movable therewith at variable speeds through the successive parts of a predetermined path, a relatively fixed abutment and a movable fulcrum interposed between the wheel and the said abutment, and power transmitting devices extending from the plunger to the wheel axis for translating the variable bodily movements of the wheel into corresponding movements of the plunger.

6. The combination with the plunger of power transmitting devices connected to the plunger and comprising a power driven wheel having a substantially constant speed of rotation around its central axis and bodily movable with said axis through a predetermined path of reciprocation, a rel-

atively stationary abutment, a shifting fulcrum interposed between the gear wheel and the said abutment, and means for translating the bodily movements of the wheel into movements of the plunger, varying relatively from each other substantially as set forth.

7. The combination with the plunger of power transmitting devices connected to the plunger and comprising a bodily movable power driven wheel which rotates around its central axis, and means for successively retarding and accelerating the bodily movements of the wheel.

8. The combination with the plunger of power transmitting devices connected to the plunger and comprising a fixed prime driving shaft, a vibrating lever arm connected to the plunger, a wheel driven from the said shaft rotating around its central axis and supported by said lever arm, and a stationary abutment with a movable fulcrum interposed between the said lever arm and said abutment, and adapted to vary the speed of the arm and the power imparted thereby, as described.

In testimony whereof I affix my signature, in presence of two witnesses.

NORRIS D. STEWART.
